CLAIM

I claim the ornamental design for a chain sprocket cover, as shown and described.

DESCRIPTION

The present application also relates to U.S. design patent application Ser. No. 29/499,541, titled “Chainsaw”.

FIG. 1 is a perspective left-rear view of the chain sprocket cover;

FIG. 2 is a bottom view of the chain sprocket cover shown in FIG. 1;

FIG. 3 is a top view of the chain sprocket cover shown in FIG. 1;

FIG. 4 is a rear view of the chain sprocket cover shown in FIG. 1;

FIG. 5 is a front side view of the chain sprocket cover shown in FIG. 1;

FIG. 6 is a left-side view of the chain sprocket cover shown in FIG. 1; and,

FIG. 7 is a right-side view of the chain sprocket cover shown in FIG. 1.
